BALLAST CAR COMPANY, OF CHICAGO, ILLINOIS, A CORPORATION OF MAINE.

DOOR LOCKING AND RELEASING MECHANISM.

1,214,285.

Specification of Letters Patent. Patented Jan. 30, 1917.

Application filed December 4, 1915. Serial No. 65,148.

To all whom it may concern:

Be it known that I, GEORGE BINET DOREY, a subject of the King of Great Britain, and resident of the city of Montreal, Province 5 of Quebec, Canada, have invented certain new and useful Improvements in Door Locking and Releasing Mechanism, and do hereby declare that the following is a full, 10 clear, and exact description of the same.

This invention relates to cars having swinging dump doors and appertains particularly to mechanism for operating and locking such doors. In cars of the identified type a difficulty experienced has been 15 the exposure of the door locking mechanism to the material discharged from the car when the doors are open, such exposure resulting in the clogging of the mechanism or in damage to same and an object of this 20 invention is to protect the door locking mechanism against any damage which might result from its exposure to the discharging material.

Another object is to provide an improved 25 door locking mechanism applicable to side discharge ballast cars.

Another object is to provide means for 30 automatically releasing dump door locking mechanism upon the entry of a plow to a car.

A further object is to provide a dump door locking mechanism which is operated by fluid pressure.

Further objects and advantages will be 35 hereinafter more fully described and particularly pointed out in the appended claims.

For full comprehension, however, of my 40 invention reference should be had to the accompanying drawings forming a part of this specification in which similar reference characters indicate the same parts and wherein:

Figure 1 is an end view partly in section 45 on line A—A Fig. 2, of a car and illustrating my improved door locking mechanism; Fig. 2 is a plan view of one end of the car partly broken away; Fig. 3 is a perspective, partly broken away, of one corner of the car, and Fig. 4 is a perspective 50 illustrating a modification.

The car a portion of which is shown by

the drawings, consists of the underframe including cross-bearers 2 and side-sills 3; side stakes 4 secured to the side-sills in part by means of vertical gussets 5 disposed longitudinally of the car, top rail 6 supported by the stakes and side doors 7 hinged to the top-rail between the stakes and adapted to swing outwardly to permit of the discharge of material from the car, my improved operating mechanism being illustrated and described in connection with side dump doors by way of example.

The floor of the car is spaced from the sides of the underframe, and, between the stakes, is inclined downwardly and outwardly as at 8 to the side sill, this construction and the particular stake construction shown not being herein claimed as they form part of a separate application filed 70 by myself on June 11, 1914 under Serial No. 844,524.

The doors are locked in their closed position by means of shafts 9 carried independently of and on the outside of the stakes 75 by arms 10 which are accommodated between the inclined floor portions 8 and extend inwardly through elongated vertical slots 11 in the gussets 5. The arms 10 are rigidly mounted upon shafts 12 rotatably 80 supported by the diaphragms 2^a of the cross-bearers and rotated preferably by steam or compressed air, being connected by links 13 to the pistons 14 of cylinders 15 which are disposed transversely of the 85 car near the sides of the latter and communicate with supply pipes 16 and 17 respectively.

There is preferably one cylinder at each 90 side of the car for the operation of the locking shaft 9 at each side, the inner ends of the cylinders of the car being connected to supply pipe 16 (connected to a suitably placed reservoir not shown) by branch pipes 18 and the outer ends of the cylinders to supply pipe 17 (connected to a suitably placed reservoir not shown) preferably by means of a branch pipe 19 which communicates with the outer end of the cylinder at one side of the car and has a 95 branch 20 extending to the outer end of the other cylinder so that the supply of fluid 100

pressure to both cylinders can be simultaneously controlled through the medium of this pipe.

The admission, through train pipe 16, of fluid pressure to the inner ends of the cylinders forces pistons 14 outwardly, moves the arms 10 upwardly and swings the shafts 9 into engagement with the door as illustrated in full lines Fig. 1, while admission, through train pipe 17, of fluid pressure to the outer ends of the cylinders, forces the pistons inwardly, moves arms 10 downwardly and swings the shafts out of locking engagement with the doors as illustrated in dotted lines Fig. 1, the outer surfaces of the stakes being tapered or beveled at the bottom at 21 to accommodate the movement of the locking shafts 9.

Although the passage through pipe 16 may be controlled and the door locking movement effected from the cab of the engine or in any other preferred manner, it is desired to control the fluid supply from pipe 17 and release the side doors automatically upon the entrance of a plow and for this reason a valve 22 is set in pipe 19 to control the admission of fluid pressure from the pipe 17 thereto and so to the outer ends of the cylinders, such valve being adapted to be operated by mechanism located at the end of the car in position to be engaged and operatively moved by the plow. It is arranged that the doors will be released upon the entrance of a plow to the car, and in this way although the side doors of all the cars may be simultaneously locked, the door unlocking operation of each car is effected separately and just when that particular car is to be plowed off.

For convenience the branch pipe 19 is connected to train pipe 17 near the end of the car, such pipe 19 having valve 22 set therein near the point of connection with the train pipe and adapted to control the supply of fluid pressure to both cylinders. The spindle of the valve has a handle thereon which is operatively connected to a member projecting into the car, adapted to be engaged by the plow, as the latter enters the car, and operate the valve.

In the preferred construction the valve is adapted to be automatically operated from either side of the car, the spindle of the valve having a double handle 23 attached between its ends thereto, to the ends of which handle links 24 are connected and extend outwardly in opposite directions respectively, through the sides of the car which are slotted at 25 for this purpose, the outer end of each link being attached to the lower end of a vertical arm 26 carried by the free end of a member 27 hinged at 28 near the end of the car and located in an aperture 29 formed in one of the end side stakes.

Each member 27 is preferably in the form

of a segmental block which snugly fills the aperture 29 and prevents leakage of material at this point, one corner of such block being hinged near the outer edge of the end stake, normally extending diagonally inwardly of the car and being yieldingly held in such position by a spring 29^a encircling a bolt 30 which passes through a slot 31 in a lip 32 presented by the block, such lip extending beyond the edge of the aperture 29 and overlapping the outer side of the end stake. Spring 29^a bears between the lip and a washer 32^a upon the outer end of bolt 30 and yieldingly maintains the block projecting inwardly of the car, the engagement of the inner side of the lip with the stake limiting inward movement of the block.

Prior to the entrance of a plow to a car pipe 16 is disconnected from its reservoir and being thus brought into communication with the atmosphere therefore permits the exhaust of the fluid pressure from the inner ends of the cylinders so that when a plow enters a car and engages one of the segmental blocks, such block is swung outwardly and moves the link 24 connected thereto outwardly to open valve 22 and in this way, upon the entrance of the plow into the car, the valve is automatically opened, fluid pressure admitted to the outer ends of the cylinders and the side doors automatically released while the initial impact of the plow with the car is cushioned by the yielding resistance of spring 29^a to the outward movement of the block.

When the plow in passing into the car, disengages from the block the latter is returned to its normal position by spring 29^a and the valve automatically closed by a spring 50 attached at its ends respectively to the valve handle and the car body. In order to provide an exhaust from the outer ends of the cylinders I provide valve 22 as a three-way valve so that when such valve closes the communication between the cylinders and supply pipe 17, the cylinders will be through pipes 19 and 20 opened to the atmosphere, this exhaust being indicated at 22^a.

While the blocks at both sides of the car may be engaged at the same time and the valve operated, it is preferred to have the operating mechanisms independent that is to say so arranged that the operation of one at one side of the car will not effect the operation of the other and entail unnecessary strain. With this object in view the links 24 are attached to the valve handle 23 by pin and slot connections 34 so that when one link attached to one end of the handle is operated to move the latter the corresponding movement of the other end of the handle is accommodated by the slotted connection therebetween and the other link without moving the latter.

From the above it will be seen that the hinged block at each side of the car is operatively connected to the controlling valve 22 and as the latter controls the supply of fluid pressure to both cylinders the automatic release of the doors at both sides of the car will be effected irrespective of which hinged block is engaged although cut-out valves 35 are set in pipes 16, 18, 19 and 20 to enable the cylinder at either side of the car to be cut off from the fluid pressure supply so that when desired the doors at one side of the car only can be operated.

A modified form of the invention where-
15 in the fluid pressure system is dispensed with is shown in Fig. 4 wherein each of the shafts 12, instead of being connected to a cylinder piston, has a lever 36 at one end, such lever extending upwardly and outwardly from the shaft to a point above the floor level where it is adapted to be engaged by a plow entering the car. Such engagement swings the lever outwardly and so rotates its respective shaft 12, lowers the locking shaft 9 connected thereto and thus automatically releases the doors.

The door locking mechanism is protected against any damage which might result from its exposure to the discharging material, the operating shaft 12, air cylinder and connections all being located beneath the floor of the car while the shaft 9, when brought to its lower position to release the doors, assumes a position beneath a portion 35 or strip 37 which preferably forms a continuation of the inclined floor portion 8 and is disposed longitudinally of and secured to the side sill at 38, extending outwardly therefrom and being inclined downwardly from the side sill to form a hood beneath 40 which the shaft 9 lies when the doors are open, such shaft being thus out of the path of the discharging material.

What I claim is as follows:

45 1. In a car, a floor, a side door, a locking shaft for locking the door in closed position and a hood beneath which such shaft is adapted to move when the door is released.

50 2. In a car, a floor, a side door, a hood, a locking shaft which is at times uncovered by the hood and adapted to lock the door in closed position, such shaft being adapted to move to a position beneath the hood when the door is released.

55 3. In a car, a floor, a side door and means for locking the door in closed position including an operating shaft beneath the floor, an arm extending outwardly through the car side and a locking shaft carried by the 60 outer end of said arm.

65 4. In a car, the underframe including a side sill, stakes secured to the underframe, a door supported between the stakes, a floor upon the underframe and spaced from the sides thereof, a side floor portion inclined

downwardly toward and secured to the side sill and having its lower edge projecting outwardly from the side sill and a shaft for locking the side door in closed position and adapted to assume a position beneath the 70 projecting edge of the side floor margin when the door is released.

5. In a car, the underframe including a side sill, stakes secured to the underframe, a door supported between the stakes, a floor 75 upon the underframe and spaced from the sides thereof, a side floor portion inclined downwardly toward and secured to the side sill and operating means beneath the inclined side floor portion for locking the door 80 in closed position.

6. In a car, the underframe, stakes secured to the underframe, a longitudinally disposed vertical gusset located between and secured to the underframe and each stake, slots in 85 said gussets, a side door supported between the stakes and means for locking the door in closed position including an operating shaft located on the inside of the gussets, arms mounted upon the operating shaft and 90 extending outwardly through said slots and a locking shaft carried by the outer end of the arms.

7. In a car, the underframe, stakes secured to the underframe and having their 95 outer sides tapered near the bottom, a longitudinally disposed vertical gusset located between and secured to the underframe and one of said stakes, a slot in said gusset, a side door supported between the stakes and 100 means for locking the door in closed position including an arm extending outwardly through said slot and a locking shaft carried by the outer end of the arm and located on the outside of the stake.

105 8. In a car, the underframe, stakes secured to the underframe and having their outer sides tapered near the bottom, a longitudinally disposed vertical gusset located between and secured to the underframe and one of said stakes, a slot in said gusset, a side door supported between the stakes and 110 means for locking the door in closed position including an operating shaft located on the inside of the gusset, an arm mounted upon the operating shaft and extending outwardly through said slot and a locking shaft carried by the outer end of the arm and located on the outside of the stake.

115 9. In a car adapted to have a plow passed therethrough, a side door, locking means for the side door, such locking means being operated by a fluid pressure.

120 10. In a car, the underframe including a side sill, stakes secured to the underframe, 125 a door supported between the stakes, a portion inclined downwardly and outwardly from the side sill and operating means beneath the inclined portion for locking the door in closed position.

11. In a car, a floor, a dump door and means for locking the door in closed position, including an arm extending outwardly through the car side and a door locking shaft carried by said arm.
12. In a car adapted to have a plow passed therethrough, means for cushioning the initial impact of the plow with the side of the car.
- 10 13. In a car adapted to have a plow passed therethrough, a spring controlled block set in the car side and adapted to cushion the impact of the plow with the car.
14. In a car, the underframe including a side sill, stakes secured to the underframe, a door supported between the stakes, a portion inclined outwardly from the car side and a shaft for locking the side door in closed position and adapted to assume a position beneath said inclined portion when the door is released.
- 15 15. In a car adapted to have a plow passed therethrough, a dump door, locking mechanism for the dump door and means for automatically releasing said locking mechanism.
16. In a car adapted to have a plow passed therethrough, a dump door, and locking mechanism for the dump door, such mechanism being adapted to be automatically released by the plow.
17. In a car adapted to have a plow passed therethrough, a dump door, mechanism for locking the door, a fluid pressure system for operating the locking mechanism and means for automatically controlling the fluid pressure system.
18. In a car adapted to have a plow passed therethrough, dump doors, mechanism for locking the doors, and means for automatically releasing the locking mechanism, including a member adapted to be engaged by a plow.
19. In a car adapted to have a plow passed therethrough, dump doors, mechanism for locking the doors, a fluid pressure system for operating the locking mechanism, a valve controlling the fluid pressure, a member projecting into the car and adapted to be engaged by a plow, such member being operatively connected to said valve.
20. In a car adapted to have a plow passed therethrough, dump doors, mechanism for locking the doors, a fluid pressure system for operating the locking mechanism, a valve controlling the fluid pressure, a spring controlled member projecting into the car and adapted to be engaged by a plow, such member being operatively connected to said valve.
21. In a car adapted to have a plow passed therethrough, dump doors, mechanism for locking the doors, and means for releasing the locking mechanism, such means being adapted to be operated by a plow.
22. In a car adapted to have a plow passed therethrough, dump doors, mechanism at each side of the car for locking the doors and means for automatically releasing the door locking mechanism simultaneously at both sides of the car.
23. In a car adapted to have a plow passed therethrough, a dump door for the car, mechanism for locking the door and means at both sides of the car for automatically releasing the door locking mechanism, the mechanism at one side of the car operating independently of the means at the other side of the car.
24. In a car, the underframe, stakes secured to the underframe, a longitudinally disposed vertical gusset located between and secured to the underframe and each stake, slots in said gussets, a side door supported between the stakes, means for locking the door in closed position including an operating shaft located on the inside of the gussets, arms mounted upon the operating shaft and extending outwardly through said slots, a locking shaft carried by the outer ends of the arms and means for automatically operating the door locking means to release the doors.
25. In a car adapted to have a plow passed therethrough, a stake, a side door, means for locking the side door and means for releasing the door including a member hinged at one end to the stake, extending into the car and operatively connected to the door locking means.
26. In a car adapted to have a plow passed therethrough, corner stakes, side doors, means for locking the doors including a fluid pressure system, valves controlling the fluid pressure and members pivoted to the stakes, projecting into the car and operatively connected to said valves.
27. In a car adapted to have a plow passed therethrough, corner stakes, side doors, locking mechanism for the side doors including an operating shaft beneath the car, arms upon and extending outwardly from the operating shaft, a locking shaft carried by the outer ends of the arms and adapted to lock the doors, fluid pressure cylinders, pistons in the cylinders and connected to said operating shaft to operate same, fluid supplying pipes leading to the opposite ends of the cylinders and valves in the pipes leading to one end of the cylinders; and segmental blocks pivoted to the stakes and operatively connected to said valves.
28. In a car adapted to have a plow passed therethrough, corner stakes, side doors, locking mechanism for the doors consisting of an operating shaft at each side of the car, arms upon and extending outwardly from each shaft, locking shafts carried by the outer ends of the arms, cylinders, pistons within the cylinders and respectively con-

nected to the operating shafts and adapted to operate same to move the locking shafts, a fluid pressure supply pipe connected to one end of each cylinder and adapted to 5 operate the pistons to lock the doors, a second fluid pressure supply pipe connected to the opposite end of each cylinder and adapted to operate the pistons to release the doors, valves controlling the fluid pressure 10 supply from said second pipe and members pivoted to the stakes, projecting into the car and being respectively operatively connected to one of said valves.

29. In a car adapted to have a plow passed therethrough, dump doors at both sides of 15 the car, locking mechanism at each side of the car, for said doors, a fluid pressure system including sections for operating the mechanisms at both sides of the car, to release said doors, means for automatically 20 controlling said fluid pressure system and cut-out valves for cutting off either section of the fluid pressure system.

In testimony whereof, I have signed my name to this specification.

GEORGE BINET DOREY.
